LOW BOILER FEED WATER RESPONSIVE SAFETY VALVES FOR SHUTTING DOWN BOILER FEED PUMP TURBINE

Edwin A. Cunningham, Jr., Whitehall, and George R. Anderson, Mount Lebanon Township, Allegheny County, Pa., assignors to Hagan Chemicals & Controls, Inc., a corporation of Pennsylvania

Application August 9, 1955, Serial No. 527,266

5 Claims. (Cl. 137—95)

This invention relates to safety devices for turbine-driven boiler feed pumps and more particularly to devices for shutting down the turbine if and when the pressure in the boiler feed line drops below a predetermined value.

An object of this invention is to provide a device having means responsive to pressure in the boiler feed line which shuts off the oil supply to the governor valve of the turbine when the pressure drops below a predetermined point.

Another object of the invention is to provide a device having a governor trip valve which is normally biased to closed position but which is manually set in open position and held in that position by a feed water pressure controlled latch which is disengaged from the valve when the pressure drops to a predetermined low point thereby shutting off the oil pressure to the turbine governor valve and stopping the turbine.

Other objects of the invention will in part be apparent and will in part be obvious to those of ordinary skill in the art to which the invention pertains from the following description taken in conjunction with the accompanying drawings.

In the drawings:

Figure 1 is a more or less diagrammatic view illustrating a steam turbine driven boiler feed water pump provided with a safety device for shutting down the turbine if and when the boiler feed water pressure drops below a predetermined low value, the safety device being arranged and constructed in accordance with an embodiment of the invention; and

Figure 2 is a view in section of the safety device illustrated in Fig. 1.

In Fig. 1 of the drawings is shown schematically a boiler 1 that supplies steam through a line 2 in which is a governor valve 3, to a turbine 4 that drives a boiler feed pump 5. The feed water is taken by pump 5 from a supply source 6 and delivered through line 7 to the boiler. A check valve 8 is in the feed line 7 to prevent reverse flow therein. The boiler 1 supplies steam for purposes other than the requirements of turbine 4. Turbine 4 as shown drives the water feed pump 5 only.

The governor valve 3 is actuated by an operator 9 which is supplied with oil at such pressures that the valve 3 is positioned in accordance with the demand for steam by the turbine. The oil for the operator 9 is supplied by a pump 11 to a safety device 12 and thence to the operator 9. The pump 11 takes the oil from a supply source not shown and delivers the oil at pressures that vary with changes in speed of the turbine.

Operator 9 comprises a cylinder 13 having a piston 14 therein that is biased in a direction to close valve 3 by means of a spring 15. The piston 14 is urged downwardly to open the valve 3 by oil admitted under pressure through a pipe 16 which is delivered through the safety trip device 12.

The piston 14 is provided with a piston 17 that extends downwardly through the bottom of the cylinder 13 and is connected to a crosshead 18 of a yoke which is con-

2

nected to the valve 3. The yoke includes rods 19 and 20 connected at their lower ends to the opposite ends of the crosshead 18 and at their upper ends to a crosshead 21. The crosshead 21 is connected to the valve stem 22 of valve 3.

The top of piston 14 is provided with a stem or rod 23 that extends upwardly through the head 24 of cylinder 13 and terminates within a housing 25. Within the housing 25 is a bellows 26 the upper end of which is connected to the rod 23 and the lower end of which is joined by welding or brazing to the head 24 to provide a fluid-tight joint and seal about the aperture through which the rod 23 extends. A spring 27 tends to elongate the bellows 26. Oil under pressure is supplied to the housing 25 which tends to push downwardly on the piston 14.

The rod 17 is sealed at the location where it passes through the base of cylinder 13 by means of a bellows 29 the upper end of which is secured in fluid-tight relation to the base of the cylinder, the opposite end of bellows 29 being secured in fluid-tight relationship with the crosshead 18.

The oil supplied to the governor operating valve mechanism 9 is derived from the pump 11 as stated. The oil 25 is delivered to an inlet pipe 30 of device 12 and discharged therefrom into a pipe 31. In pipe 31 is an orifice 32 and in pipe 16 is an orifice 33. The portion of the pipe beyond orifice 32 supplies oil through a pipe 34 to the housing 25. The extension of the pipe 31 beyond the orifice 32 supplies pilot oil to other units (not shown) of the power plant in which the turbine 4, pump 5 and boiler 1 are incorporated.

The safety trip device 12 is illustrated more in detail in Fig. 2. As there shown, the device comprises a valve body 36 having a ported sleeve 37 in the bore 38 thereof. The sleeve 37 has a bore 39 in which a valve plug 40 is disposed. The valve plug is provided with lands 41 and 42 separated by a connecting spindle 43. The sleeve 37 is provided with an inlet port 45 that communicates with 35 a port in the body to which the pipe 30 is connected and it is provided with an outlet port 46 that communicates with a port in the body to which the outlet pipe 31 is connected. The sleeve 37 is provided with annular grooves 47 and 48 that communicate with the inlet and outlet ports of the valve as shown. The sleeve is also provided with an annular groove 49 in the region of land 41. The sleeve 39 is ported at the annular groove 49 and connected to a drain pipe 50 that leads back to the supply of oil to which the intake of pump 11 is connected.

Sleeve 37 is also provided with an annular groove 51 located to the left of the inlet port 45 as shown in Fig. 2 and that groove connects the sleeve bore 39 with a drain passage 52 leading to the drain pipe 50. Thus any oil that leaks towards the left-hand end of the valve plug 55 is drained to the drain port pipe 50.

The left-hand end of valve plug 40 is connected by a pin 54 to a slide 55 disposed in the bore 38. The end of the slide 55 to which the valve plug 40 is connected is enlarged as shown and is hollow to accommodate a 60 trigger 56 that is pivotally supported by a pin 57. The trigger 56 is urged counterclockwise against a stop pin 58 by means of a slide plug 59 and a spring 60 housed in the bore of the slide 55. The spring is held in compression against the slide plug 59 by means of a screw plug 61 within the slide 55 and which is secured in position by means of a pin 62.

The slide 55 is urged to the right as seen in Fig. 2 by means of a compression spring 63 disposed about the slide 55 and within the housing bore 38. The spring is held in compression by means of a cap 64 secured to the left-hand end of the valve body as shown.

When the valve plug 40 is in the position shown in Fig. 2 the inlet port 45 is closed and the governor valve operator 9 is connected through the outlet port 46 to the drain pipe 50. When the valve plug is pulled to the left by means of the hand wheel or knob 66 to a position where the land 42 is to the left of the inlet port 45, the oil supply pipe 30 is connected to the outlet pipe 31 and the operator 9.

In order to hold the valve plug 40 in its open position a pressure actuated latch or trigger keeper 67 is provided. The keeper 67 is operatively disposed in a sleeve 68 the lower end of which is secured in a base plate 69 and the upper end of which is housed within a bellows 70. The bellows 70 in turn is housed in a housing 71. The upper end of which is closed as shown and the lower open end of which is connected in pressure-tight relationship with a flange 72 secured to a mounting plate 73. The mounting plate 73 is carried by spacers 74 through which bolts 75 extend and are threaded into the base plate 69 and the valve body.

The upper end of the bellows 70 is secured by welding or otherwise to a bearing member 77 into which the upper end of the latch 67 extends as shown. The latch 67 is urged upwardly by a compression spring 80 disposed about the sleeve 68. As shown, the upper end of the spring 80 bears against the bearing member 77 and the lower end is supported on an adjustable nut 81 by means of which the initial compressive tension in the spring 80 and the pressure at which the trigger is released may be adjusted. For the purpose of adjustment, the lower end of the nut 81 is provided with wrench sockets 83.

The housing 71 is provided with an inlet fitting 84 whereby the interior of the housing 71 may be connected to the feed water supply pipe 7 and thereby cause the bellows 70 to be compressed and the trigger keeper 67 urged downwardly.

When the pressure in the feed water line 7 is at or above a predetermined minimum value and the slide 55 is pulled to the left as shown in Fig. 2, the pressure acting on the bellows 70 will move the keeper 67 downwardly until its notched end 86 engages the end 87 of the trigger 56. When so engaged the valve plug 40 is held in open position. So long as the valve is in open position oil is supplied to the governor valve operating mechanism 9. As soon as the pressure in the feed line 7 drops below a predetermined value the bellows 70 elongates and approaches the position shown in Fig. 2, and the moment the notched end 86 of the latch 67 is disengaged from the end 87 of the trigger 56, the valve plug 40 is actuated to its closed position, whereby the oil supply to the piston 14 is shut off and the valve 3 is closed by the closing action of the spring 15. Valve plug 40 cannot be reset in open position until the condition which caused the low boiler feed pressure, usually flashing at the intake to the boiler feed pump, has been corrected.

Having thus described the invention, it will be apparent to those of ordinary skill in the art to which the invention pertains that various modifications and changes may

be made in the illustrated embodiment thereof. Therefore, what is claimed as new and desired to be secured by Letters Patent is:

- 5 1. A safety valve for shutting off the oil supply to the governor valve of a steam turbine driving a boiler feed pump in response to low pressure in the boiler feed line, which safety valve comprises a valve having a body provided with supply, outlet and drain ports, the outlet port being for supplying the governor valve, a valve plug in the body, the plug when in its off position shutting off the supply port and connecting the outlet port to drain, and when in its on position connecting the supply to the outlet port, a slide in said body connected to said valve plug, means yieldingly urging the slide in a direction to shift the valve plug to off position, a trigger pivotally supported by the slide, a trigger keeper adapted to engage the trigger when the slide is in a position to hold the valve plug in on position, means urging the keeper out of engagement with the trigger and means including a 10 pressure deflectable member adapted to be acted upon by the pressure of the boiler feed water to maintain engagement of the keeper with the trigger and thereby hold the valve in its on position so long as the pressure is above a predetermined value and to release the latch from the trigger when the feed pressure drops below said value.
- 15 2. A valve as in claim 1 in which the trigger is of substantially L-shaped, the end of one leg of which is engaged by the keeper, a slidable plug engages the upper leg of the trigger and a compression spring in the slide urges the plug against the trigger to normally maintain the trigger in a position to be engaged by the keeper.
- 20 3. A valve as in claim 1 in which the pressure deflectable means is a bellows, a housing encloses the bellows and receives the boiler feed water pressure, and in which means are provided for adjusting the keeper urging means whereby the pressure at which the trigger is released can be predetermined.
- 25 4. A valve as in claim 2 in which the keeper operates at right angles to the axis of rotation of the trigger and the keeper is provided at its trigger engaging end with notched shoulder for receiving the cooperating end of the trigger.
- 30 5. A valve as in claim 1 in which the means embodying the pressure deflectable member comprises a housing having a bellows therein, the trigger keeper extends in the bellows and is secured at one end thereto, the means urging the keeper to trigger released position is a compression spring within the bellows, one end of the spring engaging one end of the bellows and the other end engaging an adjustable support, whereby the force of the spring may be adjusted to predetermine the pressure at which the keeper is released from the trigger.
